(57) **CLAIM**

The ornamental design for an adjustable strap, as shown and described.

DESCRIPTION

FIG. 1 is a front perspective view of the adjustable strap showing my design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a rear elevational view thereof, shown in use with exemplary environmental subject matter; and,

FIG. 9 is an exploded view thereof.

The broken lines shown in the drawings are for the purpose of illustrating environmental subject matter of an exemplary cap and form no part of the claimed design.
